UNITED STATES PATENT OFFICE.

JOHN CASEY AND MURRAY S. CHISM, OF PHILADELPHIA, PENNSYLVANIA.

DESIGN FOR AN EYEGLASS-CASE.

SPECIFICATION forming part of Design No. 30,456, dated April 4, 1899.

Application filed February 14, 1899. Serial No. 705,124. Term of patent 7 years.

To all whom it may concern:

Be it known that we, JOHN CASEY and MURRAY S. CHISM, citizens of the United States, residing in the city and county of Philadelphia, State of Pennsylvania, have invented and produced a new and original Design for an Eyeglass-Case, of which the following is a specification, reference being had to the accompanying drawings, forming part thereof.

10 The leading feature of our design for an eyeglass-case is a bulging or convex cover and a tongue on the lower end of said cover.

Figure 1 represents a perspective view of an eyeglass-case embodying our design. Fig. 15 2 represents a transverse section thereof on line $x x$, Fig. 1.

In the drawings, A designates the body of

an eyeglass-case, and B the cover thereof. The body and cover have lateral bulges C and D, respectively, thereon.

On what may be termed the "lower" end of the cover is the tongue E, having confluent sides F.

Having thus described our invention, what we claim as new, and desire to secure by Letters Patent, is—

The design for an eyeglass-case substantially as shown and described.

JOHN CASEY.
MURRAY S. CHISM.
